UNITED STATES PATENT OFFICE

DANIEL F. KAY, JR., OF ASHLAND, OREGON

CONTROLLING MEANS FOR RECORDING PUMPS

Application filed July 7, 1928. Serial No. 291,115.

The object of this invention is to control or operate the registering and printing mechanism of a liquid dispensing pump of the type disclosed in U. S. application for patent, Serial No. 71,804, filed November 27, 1925—that disclosure including means for making a printed record of the number of gallons of liquid dispensed, so that the owner or other individual in authority, may be informed at all times regarding the sales made,—and the disclosure in that application further including means for preventing the operation of the pump without automatically producing a record of the kind indicated.

A further object of the present invention is to make it possible to control the device by the weight of the nozzle of the discharge duct, including a section of the latter, the removal of the nozzle from the particular supporting element to be described, setting free or placing in service, the operative elements of the recording device.

With the foregoing and other objects in view, the invention consists in the novel construction and arrangement of elements described, illustrated and claimed, it being understood that modifications may be made within the scope of the claims without departing from the spirit of the invention.

In the drawings forming part of this application,

Figure 1 is a view of the apparatus in side elevation, the dotted line position of the controlling lever being that assumed when the nozzle of the hose is suspended from the lever.

Figure 2 shows the operative elements chiefly in front elevation, a fragmentary portion of the pump housing being in vertical section.

Figure 3 is a plan view of the element supporting the hose in the manner shown at the left of Figure 1.

Figure 4 is a section on line 4—4 of Figure 1.

Figure 5 is a section on line 5—5 of Figure 2, showing details of the nozzle supporting device on the end of the main lever of Figure 1 or Figure 2.

Figure 6 is a view in vertical section transversely of the shaft mounting the rotary ele-

ments of the printing mechanism, and the view shows a feeding pawl and an upper holding pawl for the ratchet wheel of the mechanism here referred to.

Figure 7 is a detail view showing the angle lever at the left of Figure 6, this lever being adapted to be rocked by a member assumed to be in the path of a movable element of the pump.

It is assumed that a liquid dispensing pump, of standard construction, is inoperative until released by an engaging element, (carried by shaft 5), and designated 7 in Figure 2 of the drawings. This element 7 is adapted to engage some movable element of the pump, in order to effect the purpose indicated.

When shaft 5 is free to rock, the hose being removed for the purpose of filling a fuel tank on a motor car,—the spring 6, of the tension type, acting on arm 13 produces rocking movement of shaft 5, and the engaging device designated 7 is moved to release position, thereby permitting of the operation of the pump, for the purpose indicated.

Shaft 5 carries a controlling arm 13' rigidly mounted as shown at 13', on an end of said shaft, and a hose supporting element 75 is pivotally mounted at 76 on arm 13', having its movement limited by stop 77, and a spring 78 tending to retain the supporting device in the position of Figure 1, so that the hose and nozzle may readily and conveniently be suspended in the manner shown in dotted lines at the left of Figure 1. One end of spring 78 is connected with lever or arm 13', and the other end is connected with element 75 in any suitable manner as by means of a lug 79.

The hose supporting device 75 includes a U-shaped frame, the middle portion of which is designated 80, the side members 81 being deflected at 82 and inwardly deflected at an angle as shown at 83. The portions 83 engage the coupling or other device 84 between the end of the hose 85 and the nozzle member 86.

The weight of the hose and nozzle is sufficient to rock shaft 5 and cause the engaging device 7 to come into obstructive relation to

an operative or movable element of the pump mechanism, (not shown) so that when the hose and nozzle move the lever arm 13' to the dotted line position of Figure 1, shaft 5 is partly rotated, for the purpose indicated.

5 The pump is now inoperative until the hose is taken down for dispensing gasoline or the like.

10 The automatic control here disclosed takes the place of the manual control thru the handle employed in the structure described in the application for patent above referred to. The operation of the apparatus will be referred to briefly as follows:—

15 When the hose is suspended from arm 13', member 7 is in obstructing relation to some vital element of the pump, this element being released by the removal of the hose. When so removed, and shaft 5 rocks under spring 20 action, the roller 10 carried by the arm 9 fixed on shaft 8, comes into engagement with the end 66 on the arm 65 resulting in swinging movement of the latter, so that roller 67 will come into engagement with ribbon 68, forcing the latter into engagement with the paper strip 24.

25 As the pump is operated, and as every gallon or other unit is dispensed thereby, the plunger 54 will be operated, so that the movement of the actuating element of the pump 30 device will be imparted to the angle lever 49. The result is that at every movement, up and down, of the lever 49, the rod 46 carrying the actuating pawl 45 will cause the latter to engage 35 the ratchet wheel 44 on the axis of the printing wheel 33 and move it one step. The parts are so timed that as each gallon, or other unit, is pumped, the element 33 and printing wheel 34 will be moved one step, the 40 retaining pawl 57 acting to prevent retrograde movement.

45 The number of gallons or other units pumped by the mechanism with which the device is associated, will be indicated by the type face on the printing wheel 33. After 50 the transaction has been completed, it is intended to swing the lever arm 13' to the horizontal position of Figure 1. When this is done the roller 10 carried by the arm 9 will engage against the trip arm or finger 66 of the cam member 65 and swing the latter so that the roller 67 carried thereby will travel along the ribbon 68 and force it into actual engagement with the paper strip 24 and the 55 type wheel so that a printed record will be made.

56 Arm 63 engaged by cam 12 will move arm 60 thereof upwardly into engagement with the roller 59, so that the retaining pawl 58 60 will be lifted out of engagement with the ratchet 44, permitting the element 33 to be returned to normal position. By this means the entire mechanism is reset for the next printing operation at the time the next transaction or sale of gasoline or other liquid occurs.

At each printing operation it is of course apparent that the number of gallons will be printed upon the paper strip 24.

Having described the invention what is claimed is:—

1. In a controlling device for dispensing and recording mechanism, means for obstructing the dispensing mechanism, a shaft mounting said means, an arm rigid with reference to the shaft, a U-shaped frame rotatable with reference to the arm, a spring connected with the frame and with the arm, and means for limiting the movement of the frame.

2. In a device of the class described, a shaft 70 for operating the printing mechanism of a recording device, an arm rigid with reference to the shaft, a U-shaped frame carried by the arm, the frame including elements deflected toward each other to form engaging edge portions, said frame having rotatable movement, and a resilient device for determining the position of the frame, when free to rotate with reference to the arm.

80 In testimony whereof I affix my signature.

DANIEL F. KAY, Jr.
